UNITED STATES PATENT OFFICE

109,897

DESIGN FOR A FINGER BUTTON FOR A SELECTOR MEMBER OF A RADIO TUNING DEVICE

Richard C. Marholz, Chicago, Ill., assignor to Belmont Radio Corporation, Chicago, Ill., a corporation of Illinois

Application March 30, 1938, Serial No. 76,191

Term of patent 7 years

To all whom it may concern:

Be it known that I, Richard C. Marholz, a citizen of the United States, residing at Chicago, in the county of Cook and State of Illinois, have invented a new, original, and ornamental Design for a Finger Button for a Selector Member of a Radio Tuning Device, of which the following is a specification, reference being had to the accompanying drawing, forming part thereof, in which:

Figure 1 is a side elevational view of the finger button for a selector member of a radio tuning device showing my new design.

Figure 2 is a top plan view of the button.

Figure 3 is a front elevational view thereof.

I claim:

The ornamental design for a finger button for a selector member of a radio tuning device, as shown.

RICHARD C. MARHOLZ.
